WINDBREAKER FOR VEHICLES

Marshall S. De Vaughn, P.O. Box 26,
Hope Hull, Aa. 36043

Filed Jan. 21, 1974, Ser. No. 434,885

Int. Cl. D12—16

U.S. Cl. D12—93

Fig. 1

Fig. 2

Fig. 3

FIG. 1 is a side elevational view of a windbreaker for vehicles showing my new design, the opposite side being a mirror image thereof, and the broken lines being for illustrative purposes only;

FIG. 2 is a front elevational view thereof; and

FIG. 3 is a top plan view thereof.

I claim:

The ornamental design for a windbreaker for vehicles, as shown and described.
